UNITED STATES PATENT OFFICE.

WILLIAM M. RICKETTS, OF COLUMBUS, OHIO, ASSIGNOR OF ONE-HALF
TO COLONEL E. BRIGHT, OF COLUMBUS, OHIO.

INHALER.

SPECIFICATION forming part of Letters Patent No. 784,632, dated March 14, 1905.

Application filed June 13, 1904. Serial No. 212,238.

To all whom it may concern:

Be it known that I, WILLIAM M. RICKETTS, a citizen of the United States, residing at Columbus, in the county of Franklin and State of Ohio, have invented a certain new and useful Improvement in Inhalers, of which the following is a specification.

My invention relates to the improvement of inhalers of that class which are adapted to be supported or suspended from the nose of the person using the same.

The objects of my invention are to provide an inhaler of this class of improved construction and arrangement of parts; to so construct my device as to facilitate its ready adjustment to the nose of the wearer; to so support the inhaler as to permit of the adjustment of the body thereof to a proper position for inhaling the vapor therefrom either through the nostrils or mouth; to so connect the nose-clamp with the supporting-wires of the inhaler-body as to permit of said clamp being swung to the desired clamping position, and to produce other improvements the details of which will be more fully pointed out hereinafter. These objects I accomplish in the manner illustrated in the accompanying drawings, in which—

Figure 1 is a front elevation of my improved inhaler. Fig. 2 is a side view thereof at right angles with that shown in Fig. 1. Fig. 3 is a transverse section on line *xx* of Fig. 1, and Fig. 4 is a central vertical section on line *yy* of Fig. 1.

Similar numerals refer to similar parts throughout the several views.

In carrying out my invention I employ a suitably-shaped receptacle or case 1, which is designed to contain a desirable medicament or medicated material. The receptacle 1 is closed at its lower end and open at its upper end, and its rear wall is formed with the desired number of perforations 2, these latter being indicated in Figs. 3 and 4 of the drawings. The opposite sides of the receptacle 1 are formed with parallel vertical grooves or recesses 3, which extend throughout the length of the receptacle. 4 represents a wire support which, as shown, is bent to a substantially yoke form

and which has its vertical members extending through the side grooves 3 of the receptacle 1, said receptacle being thus slidably supported between said wire members. The ends of the wire 4 are hooked into connection with laterally-projecting studs 5 of a bowed spring-strip 6, the latter being in the form of an eyeglass nose bridge or yoke and terminating in inclined nose-clamping pieces or guards 7 of the character ordinarily employed in connection with eyeglasses or spectacles. In their upper portions the vertical members of the wire 4 are looped to form laterally-extending eyes 8.

In utilizing my invention the spring 6 is made to bridge the nose of the patient in the usual manner, while the clamps 7 are held by said spring in clamping engagement with opposite sides of the nose. In this manner the case or receptacle 1 is suspended beneath the nostrils in proper position to insure the inhaling of the vapor or medicated air arising from the contents of the receptacle. In view of the fact that the receptacle is slidably mounted between the wire members it will be understood that the position of the receptacle may be adjusted vertically, said receptacle being held in the position to which the same is moved by the clamping or spring action of said wire members.

Owing to the formation of the perforations 2 in the rear wall of the receptacle, it will be observed that the latter may be so adjusted as to be supported opposite the mouth of the wearer, thus permitting of the inhalation being accomplished either through the nostrils or mouth. The hook connections between the wire members and the stud 5 are such as to permit of the nose-engaging device, which comprises the spring 6, clamps 7, and stud 5, being swung so as to stand at desirable angles with relation to the supporting wire-members and permit of such adjustment of the nose-clamping parts as will facilitate the engagement of noses of different conformation.

It will be understood that the loops or eye projections 8 may have connected therewith the ends of a suitable retaining-cord, which,

if desirable for use, may pass about the ears or head of the patient.

From the construction which I have described it will be seen that a comparatively simple and inexpensive device is produced which may be readily connected with and properly supported from the nose of a patient and that the same will be of great utility in the treatment of catarrh, asthma, hay fever, lung, throat, and other troubles where it is desirable to treat the parts by inhalation of medicated air or vapor.

Having now fully described my invention, what I claim, and desire to secure by Letters Patent, is—

1. In an inhaler, the combination with a receptacle and supports rising therefrom, of a spring-actuated nose-clamping device connected to and disposed between the supports.
2. In an inhaler, the combination of a receptacle, a yoke-like support between the vertical members of which said receptacle is slidably mounted, and a spring-actuated nose-

clamping device having a hinged connection with said supports.

3. In an inhaler, the combination of a receptacle having its opposite sides grooved, a yoke-like support, the upright members of which lie in the opposing grooves of said receptacle, and a nose-clamping device connected with the upper portion of said support and comprising a bowed spring, clamping-pieces, and projecting studs, substantially as described.

4. In an inhaler, the combination with a receptacle having one of its sides perforated and having its sides at right angles therewith provided with vertical grooves, of a support comprising a yoke-like frame the vertical members of which enter said receptacle-grooves, and a spring-actuated clamping device connected with the ends of said support.

WILLIAM M. RICKETTS.

In presence of—

C. C. SHEPHERD,
